(57) CLAIM

The ornamental design for a shelter with ground cover, as shown and described.

DESCRIPTION

FIG. 1 is a perspective view of my design for a shelter with ground cover.

FIG. 2 is a front view of my design shown in FIG. 1.

FIG. 3 is a rear view of my design shown in FIG. 1.

FIG. 4 is a top view of my design shown in FIG. 1.

FIG. 5 is a bottom view of my design shown in FIG. 1.

FIG. 6 is a right side view of my design shown in FIG. 1, the left side view is a mirror image of the right side view.

FIG. 7 is perspective view of my design shown in FIG. 1 shown in a collapsed configuration.

FIG. 8 is a top view of the configuration shown in FIG. 1.

FIG. 9 is a bottom view of the configuration shown in FIG. 1.

FIG. 10 is a front view of the configuration shown in FIG. 1.

FIG. 11 is a rear view of the configuration shown in FIG. 1.

FIG. 12 is a right side view of the configuration shown in FIG. 1; and,

FIG. 13 is a left side view of the configuration shown in FIG. 1.

The shelter with ground cover is shown with symbolic breaks. The appearance of any portion of the article between the break lines form no part of the claimed design.

The broken lines illustrate environmental structure of the shelter with ground cover that form no part of the claimed design.

1 Claim, 7 Drawing Sheets
